UNITED STATES PATENT OFFICE.

MARTIN DEACON AND WILLIAM GORE, OF LONDON, ENGLAND.

APPARATUS FOR ADDING REAGENTS TO LIQUIDS OR FOR MIXING LIQUIDS.

1,056,780.

Specification of Letters Patent.

Patented Mar. 25, 1913.

Application filed April 30, 1912. Serial No. 694,267.

To all whom it may concern:

Be it known that we, MARTIN DEACON and WILLIAM GORE, subjects of the King of England, and both residing at London, in 5 England, have invented certain new and useful Improvements in Apparatus for Adding Reagents to Liquids or for Mixing Liquids, of which the following is a specification.

10 This invention relates to apparatus for adding coagulants or other reagents to liquids or for mixing liquids and has particular reference to apparatus in which the difference of pressure between two points, one on 15 each side of a restriction in the main pipe, causes a portion of the liquid to flow through a chamber containing the reagent and to carry such reagent into the main stream of the liquid. In apparatus of this 20 kind the chamber containing the reagent has to be recharged periodically and there is a possibility of the new charge displacing the liquid saturated with the reagent and wasting it, or else causing an undue quantity to 25 pass into the main liquid.

One of the objects of the present invention is to obviate this disadvantage by the provision of a second chamber communicating with the first chamber containing the reagent 30 through a valve-controlled connection, the arrangement being such that the recharging of the chamber can be caused to displace liquid in the second chamber. As the second chamber normally contains water 35 or other liquid to be treated, uncharged with the reagent, the displacement of liquid from the second chamber does not cause any waste of the reagent.

Another feature of the invention is the 40 provision of a mixing chamber or vessel by means of which the density of the reagent-carrying liquid is maintained constant. As the volume of the reagent-carrying liquid added to the main liquid, is usually made 45 proportional to the amount of liquid passing through the main, it is of importance that the strength or density of the solution containing the reagent should be maintained constant.

50 In the accompanying drawings which illustrate one construction of apparatus according to this invention, Figure 1 is an elevation, some parts being shown in section. Figs. 2 and 3 are sectional views on 55 a larger scale showing one of the valves in two positions, and Fig. 4 is an elevation

partly in section showing another part of the apparatus which can be used in conjunction with the apparatus shown in Fig. 1.

With reference first to Figs. 1, 2 and 3, 60 the main pipe A conveying, for example, the supply of unfiltered water to a filter is provided with a restriction in the form of a plate B having tubular openings B'. These tubes B' lead into other short tubes 65 B² which, in the example illustrated, are of slightly larger diameter. The direction of flow of the water in the main A is in the direction of the arrow a in Fig. 1, and from the high pressure side of the restriction 70 formed by the plate B and its openings, a pipe C leads to a six-way valve or cock D. This cock is also in communication with the low pressure side of the restriction by means of a pipe E. At some convenient place preferably adjacent to the restriction in the main pipe, two vertical chambers are provided one of these F, being furnished with a removable cover F' and adapted to contain some reagent for example, a coagulant. The 80 other vessel G which is connected to the vessel F through the six-way cock D is intended to contain only water or other liquid which is passing through the main A. By reference of Fig. 1 it will be seen that a 85 pipe G' connects the top of the vessel G to the cock D, a similar pipe F² serving to connect the cock with the top of the vessel F. A pipe H connects the cock to the bottom of the vessel G and the lower portions 90 of the two vessels F and G are connected by a pipe J in which is interposed a regulating valve J'. The cock is shown in section in Figs. 2 and 3, Fig. 2 illustrating the position of the cock during the normal operation 95 of the apparatus and Fig. 3 showing its position when the apparatus is being recharged. When the cock D is in the position illustrated in Fig. 2 it will be seen that the pipes F² and E are placed in communication with each other, the pipes C and G' 100 being also connected.

The operation of the apparatus is then as follows:—Water or other liquid from the high pressure side of the restriction in the main pipe A passes through the pipes C and G' into the top of the second chamber G, out at the bottom of that chamber through the pipe J and regulating valve J' into the lower extremity of the chamber F 110 whence it rises through a grid F³, which is used to support the reagent when a solid

or crystalline substance is used. From the upper end of the chamber F the liquid charged with the reagent, passes through the pipes F² and E to the low pressure side of the restriction in the main pipe. It will be seen that the entrance for the liquid from the pipe E in the main A is arranged so that the liquid passes into the larger tubes B², and the flow of the reagent-saturated liquid is thus assisted by the passage of the unfiltered liquid through the smaller tubes B'. When it is desired to replenish the chamber F with the reagent the cock D is moved into the position shown in Fig. 3, that is to say, when the pipe F² is placed in communication with the pipe H and the pipe G' connected to a pipe K leading to waste. When the cock is turned into this position the cover F' is removed and fresh reagent placed in the vessel F. Any solution saturated with the reagent, which may be in the vessel F, is displaced and passes through the pipes F² and H into the bottom of the second chamber G. In this chamber it will displace water which will pass out through the pipes G' and K to waste.

It will be seen from Fig. 1 that a second set of two chambers F⁴ and G⁴ is provided connected to the main pipe A and to each other in a manner similar to that described with reference to the chambers F and G. This second set may be used alternatively with the first set or both sets may operate simultaneously, for example, one set may supply a suitable coagulant to the water and the other set may provide lime or other alkali.

If the apparatus shown in Fig. 1 be used alone, it is advisable that the liquid passing through the pipe E and carrying the reagent, should be a saturated solution of the reagent, but there are difficulties in connection with the use of a saturated solution. In the first place such a solution is liable to crystallize out and clog the small passages of the apparatus, and also in many cases the proportion of reagent required is so small that there is difficulty in adding it in the form of a saturated solution. To overcome these difficulties it is preferred to use in conjunction with the apparatus shown in Fig. 1, the mixing and density regulating apparatus shown in Fig. 4. This comprises a chamber or casing L having an upper inlet L' for the dense or saturated liquid and another inlet L² at the bottom, for water or less dense liquid. These two inlets are controlled by a float M, preferably in the form of a light cylindrical body, which can be weighted to suit the specific gravity of the mixture which is to be used. At the top of the float M is a conical valve M' working in conjunction with the inlet L', while the bottom of the float is provided with a similar valve M² to control the inlet

L². For the sake of clearness this apparatus is shown in Fig. 4 separate from the apparatus in Fig. 1, but it is to be understood that the pipe E of Fig. 1, leading from the six-way cock D could be cut and connected to the pipe E' of Fig. 4, so that when the cock D is in the position illustrated in Fig. 2, the liquid saturated with the reagent coming from the vessel F through the pipes F² and E, would flow through the pipe E' into the regulating vessel L by way of the inlet L'. The second inlet L² of the regulator L is intended to be connected as shown in Fig. 4 to the main A on the high pressure side of the restriction. Thus the inlet L² may be connected to the pipe C. The vessel L is provided with an outlet L³ conveniently midway between the inlets L' and L². The mixture flowing from this outlet passes through a pipe E² and enters the main A on the low pressure side of the restriction. Thus the pipe E² may be regarded as forming the lower end of the pipe E of Fig. 1. It will be understood that if the weight of the float M is properly adjusted the density of the liquid passing out of the vessel L, by way of the outlet L³, can be kept at any predetermined value. If the mixture in the chamber L is too dense the float will rise and will tend to shut off the supply of dense liquid from the inlet L' and to increase the flow of the water or less dense liquid coming in at the inlet L². If, on the other hand, the solution is too weak the float M will sink, opening the inlet L' for the dense liquid and tending to close the inlet for the water. In order that, when the float M sinks, its entire weight shall not be taken by the pointed valve M² it is preferred to employ a construction such as that illustrated in which, after the inlet L² has been closed, the weight of the cylinder is taken upon a screwed cap N or other rigid shoulder with which the nut or collar N' on the float M, comes into contact. One or other of the inlets L', L² may be adjustable in order to vary the travel of the float.

It is preferred to employ strainers at each of the inlets and the outlet of the vessel L, for the quantity of reagent required is often so small that very minute orifices are necessary and consequently it is well to avoid any risk of clogging. Such strainers are shown at O in Fig. 4 and cocks may be provided on each side of each strainer, so that any strainer may be removed and cleaned without wasting the liquid.

The cock shown at P in Fig. 4 is intended to provide a graduated outlet for the mixture passing from the vessel L. The cock may conveniently comprise a plug tap having a series of circular orifices so arranged that any one of them can be brought into line

with a straight-through passage. Any well known arrangement of this kind may be employed and obviously it may be inserted at the point where the liquid leaves the 5 main A, that is in the main pipe C, instead of at the point where the liquid returns to the main.

The float itself may be made of some material which is not acted upon by the liquid 10 under treatment, or may be coated with some such material. Hard rubber or vulcanite may be used for the valves and their seatings.

What we claim as our invention and desire to secure by Letters Patent is:—

1. In apparatus for adding reagents to liquids or mixing liquids the combination of a chamber adapted to contain the reagent, a second chamber adapted to contain 20 the liquid under treatment, a main for the liquid having a restriction to give a difference of head, connections between the chambers and the main and a cock controlling the connections, such cock and the connections being so disposed that the recharging of the first chamber will only displace liquid uncharged with the reagent in the 25 second chamber.

2. In apparatus for adding reagents to 30 liquids the combination of a chamber adapt-

ed to contain the reagent, a second chamber adapted to contain the liquid under treatment, a main for the liquid having a restriction to give a difference of head, connections between the two chambers and between the chambers and the high and low pressure sides of the restriction in the main and a cock controlling such connections, 35 said cock and connections being so disposed and arranged that in one position of the cock the liquid to be treated passes from the high pressure side of the restriction to the second chamber, the liquid displaced from the second chamber entering the first chamber and displacing liquid charged with reagent and causing it to pass to the low pressure side of the restriction, while in the other position of the cock the reagent can be added to the first chamber and displaces liquid uncharged with the reagent from the 45 second chamber.

In testimony whereof we have signed our names to this specification in the presence of two subscribing witnesses.

MARTIN DEACON.
WILLIAM GORE.
